APPARATUS FOR UNLOADING HIGH EXPLOSIVE SHELLS

Filed April 17, 1923. 3 Sheets-Sheet 3

UNITED STATES PATENT OFFICE.

RICHARD H. BOTS, OF NEW YORK, N. Y., ASSIGNOR TO COLUMBIA SALVAGE CORPORATION, OF NEW YORK, N. Y., A CORPORATION OF NEW YORK.

APPARATUS FOR UNLOADING HIGH-EXPLOSIVE SHELLS.

Application filed April 17, 1923. Serial No. 632,711.

To all whom it may concern:

Be it known that I, RICHARD H. Bots, a citizen of the United States, and resident of the borough of Manhattan, in the city, county, and State of New York, have invented certain new and useful Improvements in Apparatus for Unloading High-Explosive Shells, of which the following is a specification.

10 The main object of this invention is to provide a new and useful apparatus for unloading high explosive shells. It is necessary that the entire high explosive charge be removed from the shells in order that the 15 empty shells may be safely melted or reduced in a blast furnace or otherwise. The materials forming the charge are valuable and may be used commercially when separated.

0 A high explosive shell for artillery use, consists, ordinarily, of a hollow steel shell 25 filled with a charge of high explosive, said charge being substantially solid when cooled and forming a practically homogeneous hard mass which substantially fills the shell. The shell is usually pointed at one end and said pointed end is known as the nose. In the nose is formed a longitudinally extending threaded aperture in which is screwed a 30 flanged adapter ring; and said ring carries a booster casing and a fuse. Before the shells can be unloaded, that is to say, the charge removed, the adapter ring carrying the booster casing and the booster charge must be 35 removed. The fuse, or fuse stock, is inserted only when making the shell ready for firing. A great many of these high explosive shells are charged with amatol, pure trinitrotoluol (TNT), picric acid, ammonium picrate or 40 with a mixture of TNT and picric acid. Amatol is a mixture of ammonium nitrate and TNT in proper proportions. These high explosive charges are fluid or semi-fluid at certain temperatures and are usually poured 45 into the shell in a fluid or semi-fluid state. When the charge cools it solidifies within the shell and becomes a substantially solid and homogeneous mass of material which completely fills the entire shell except for a small space at the nose which space is designed to receive the booster casing.

The main purpose of this invention is to provide an apparatus for safely, completely and quickly removing high explosive charges

from the shells, and separating the TNT 55 from the other elements of the charge.

In the drawings, Fig. 1 is a longitudinal vertical sectional view, partly in side elevation, of an apparatus for carrying out the 60 invention;

Fig. 2 a plan view of the apparatus;

Fig. 3 a vertical sectional view taken on the line 3—3 of Fig. 2; and

Fig. 4 a vertical transverse sectional view taken on the line 4—4 of Fig. 2. 65

In carrying out this invention the adapter ring and the booster casing are first removed thereby leaving the aperture in the nose of the shell open so that access may be had therethrough to the interior of the shell. 70 The shells are arranged in an inverted position with their open pointed ends downwardly. The inverted shells may be supported in a rack 1 which is provided with apertures through which the body of the 75 shell may pass freely. Each shell, near its base, is provided with a ring designed to take the rifling in the gun barrel and this ring forms a convenient shoulder to engage the upper surface of the rack so that the shell 80 will be suspended in the opening in the rack. The rack may be of any desired size to support a number of shells in inverted position. The rack 1 is preferably supported in a tank 2. As shown in the drawing 85 the ends of the rack rest on brackets secured to the sides of the tank so that the rack may be bodily removed from the tank. The rack may be filled with shells before it is placed in the tank or the shells may be 90 placed individually in the rack within the tank. The tank is provided with a cover 3 which may be closed after the rack and the shells are in place. A suitable quantity of water is placed in the tank and the water 95 level is maintained just below the lower open ends of the shells in the rack. It is desirable to maintain an air space between the lower ends of the shells and the surface of the water. The outlet 4 is arranged to 100 maintain the proper constant water level within the tank.

Extending through the tank, below the water level is a steam pipe 5 which may be connected to any suitable source of steam 105 pressure. The pipe 5 is provided with upwardly extending vertical steam nozzles 6. These nozzles are axially in line with the

shells when the shells are in position within the tank. One nozzle is provided for each shell and its upper end is directed to the center of the opening in the shell. The nozzles terminate below the water level, that is to say, the nozzles are submerged at the normal water level in the tank. In the lower part of the tank, above its bottom, is arranged a steam coil 7. This coil may be connected to any suitable steam supply. As shown in the drawings this steam coil is connected to the upper part of the tank by means of a pipe 8 so that said coil will be supplied with steam from the steam supply in the tank above the water. The end of the coil is carried out from the tank in the form of a discharge nozzle 9 in order to insure the circulation of steam through the heating coil. The bottom of the tank is provided with an outlet 10 which is connected to the means for separating the TNT from the other materials forming the charge. The outlet 4 is protected by a water seal or trap 11 to prevent the escape of steam there-through.

In operation the adapter ring and booster casing must be first removed from the shell. The shells in this condition are inverted and placed in the rack 1 with their lower open ends directly over the steam nozzles 6. Sufficient water is placed in the tank to bring the water level up to normal, which will be below the lower ends of the shells. The cover 3 of the tank 2 is then closed. Steam is now admitted to the pipe 5 and blows out through the nozzles 6. The steam jets force a certain amount of water and a certain amount of steam up into contact with the solid mass within the shells. The mass within each shell is subjected to heat and water, the pressure of the steam forcing the water into the shell and producing a scouring action. This results in a softening or liquefying of the mass and causes it to drop down through the lower open end of the shell and into the water. There will be a certain amount of steam condensed but the space in the tank above the water level will be eventually filled with steam and will serve to heat the exterior of the shells. Steam will flow from this steam space of the tank through the pipe 8 into the coil 7 and serve as an additional means for heating the water. The water level will be maintained substantially uniform and normal by an out flow through the overflow pipe 4. It is manifest that as the charge from the shells drop down into the water, and as the steam condenses, the water level would rise if it were not for the overflow pipe 4.

The principal function of the steam coil 7 is to keep the water in the tank near its boiling point and, at the same time, to keep the TNT in a melted condition. By keep-

ing the water near its boiling point there will be very little condensation from the steam jets. The result of this is that when an amatol charge is treated, an ammonium nitrate solution is obtained which is concentrated and a good marketable product. 70

The TNT of the explosive charge will drop to the bottom of the tank and will be maintained at a high temperature, or at a sufficient temperature to keep it liquid, by 75 the steam coil 7. The steaming operation will be maintained until the shells are free of the solidified charge. The cover 3 may then be opened and the rack of empty shells removed and a rack of untreated shells 80 placed in the tank.

The apparatus shown in the drawings and described herein for liquefying and removing the charges from the shells is shown in my co-pending application, Serial 85 #629,364, filed April 2, 1923 and will not be claimed herein.

The apparatus for separating the TNT from the other materials of the charge consists of an open main settling tank 15 which receives the TNT from the outlet 10, said outlet entering the tank 15 near its bottom. Close to the tank 15 is arranged a deep settling well 16 which is considerably below the bottom of the settling tank. The bottom of the settling tank is in connection with the settling well through pipe 17, said pipe entering the settling well a considerable distance above the bottom thereof. Extending centrally down in the settling well 16 is a discharge pipe 18, the lower end of said pipe being open and arranged close to the bottom of the well. The upper end of this discharge pipe is carried out through the side of the settling well near the top 100 thereof and its outer end is provided with a discharge nozzle 19, preferably a length of rubber hose. This discharge nozzle is arranged to deliver material into the boxes 20 arranged on a conveyor 21, of any suitable form. The boxes are arranged to be passed under the nozzle 19 to be filled and then moved along on the conveyor. 105 110

Arranged in the main settling tank 15 is a steam coil 22 for the purpose of keeping the contents heated to the desired temperature so that the TNT therein will remain fluid. A heating coil 23 extends down to the bottom of the settling well 16 for the purpose of maintaining the TNT fluid 120 and at the desired temperature. The steam pipe 5 and the coils 22 and 23 are suitably connected to a steam generator 24. 115 125

The TNT is of greater specific gravity than the other materials in the explosive charges and will drop to the bottom of the tank 15 and pass from there into the settling well. When the apparatus is initially charged the settling tank and the well 16 will be filled with water to the level of the 130

overflow pipe 4 and this level will be maintained, the overflow pipe 4 preventing any material rise of the water level in any of the connected tanks.

5 The discharge pipe 18 is so arranged and proportioned as to length that the column of liquid in the settling well will be of sufficient height to force the TNT from the bottom of the settling well up through the 10 discharge pipe and out through the nozzle 19. The column of TNT will be maintained substantially uniform in height for the reason that when said column reaches a predetermined height within the well it will 15 be of sufficient weight with the added weight to the other liquid in the well, to cause the TNT to move upwardly through the discharge pipe and this discharge will be automatic and continuous so long as the 20 TNT is discharged into the well through pipe 17 from the settling tank.

The liquid in the tank 2 above the liquid TNT on the bottom of the tank, will contain a certain amount of TNT which will 25 be carried with said liquid through the overflow pipe 4. This TNT is usually mixed with foreign matter and it is desirable to recover it separately and independently of the purer TNT which passes to the settling tank 15. The overflow or discharge through pipe 4 is carried into supplemental settling tanks 25 and 26. These tanks are connected together by an overflow pipe 27. Tank 26 is provided with a discharge pipe 35 28, this latter pipe and pipes 27 and 4 being all on the same level so that the level of the liquid in all of the tanks will be the same. In the tanks 25 and 26 are arranged pipe coils 29, said coils being connected to 40 the steam generator and to a cold water supply by suitable pipes. In these connections are arranged valves 30 and 31 by means of which cold water or steam may be admitted to the coils 29 as desired and for the purpose hereinafter described.

A supplemental settling well 32 is arranged close to the settling tank 25, and the bottom of the latter tank is connected to the settling well by a pipe 33. The supplemental settling well is precisely like the settling well 16 and is provided with a discharge pipe 34. The main and supplemental settling tanks are provided with water jackets 35 around their lower portions and these water jackets are provided with steam coils 36 for the purpose of maintaining them at the proper temperature to keep the TNT in said wells fluid. The coils 36 are connected to the steam supply 60 through pipes 37.

Some TNT either in suspension or in solution, will pass through the overflow pipe 4 to the settling tanks 25 and 26. The TNT in suspension will gradually settle to the 65 bottom of said tanks. To assist in throwing

down the TNT which is in solution cold water is caused to pass through the coils 29. When a sufficient quantity of the TNT is collected in the tanks 25 and 26 the cold water will be cut off from said coils and 70 steam admitted thereto. The steam will raise the temperature of the contents of the tanks sufficiently to liquefy the TNT and cause it to run into the supplemental settling well 32. From this well the TNT will 75 be discharged through pipe 34 and the discharge nozzle 34^a connected thereto. The TNT which will settle in the tanks 25 and 26 contains foreign materials and is therefore of lower quality than the TNT discharged from the main settling well 16 and for that reason it is desirable to discharge it separately, and keep it from mingling with the better grade of material. After the TNT has been discharged from the tanks 80 25 and 26 the steam supply is cut off from the coils 29 and cold water again supplied thereto.

The discharge through pipe 28 is delivered into a collecting tank 38 from which 85 it may be pumped into a large storage tank 39.

The materials other than TNT contained in the explosive charges will be in solution in the liquid in tanks 25 and 26, and of course in tank 2, and the outflow from tank 26 may be treated in any suitable manner if it be desired to recover those materials from that liquid.

What I claim is:

1. An apparatus for separating liquid TNT from liquids of lighter specific gravity, comprising a settling tank, a settling well the bottom of said well being below the bottom of the settling tank, a pipe connection from the bottom of the settling tank to the settling well said pipe entering the settling well a considerable distance above the bottom thereof, means for maintaining a normal liquid level in said well, and a discharge pipe in the settling well the lower end of said pipe being open and arranged near the bottom of the settling well, the upper end of said discharge pipe being carried through the wall of the settling well 105 above the connection between the tank and the well and below the normal liquid level of said well.

2. An apparatus for separating liquid TNT from liquids of lighter specific gravity, comprising a settling tank, a settling well the bottom of said well being below the bottom of the settling tank, a pipe connection from the bottom of the settling tank to the settling well said pipe entering the 110 settling well a considerable distance above the bottom thereof, means for maintaining a normal liquid level in said well, a discharge pipe in the settling well the lower end of said pipe being open and arranged 115

near the bottom of the settling well, the upper end of said discharge pipe being carried through the wall of the settling well above the connection between the tank and the well and below the normal liquid level of said well, and heating coils in said tank and in said well.

3. An apparatus for separating liquid TNT from liquids of lighter specific gravity, comprising a settling tank, a settling well the bottom of said well being below the bottom of the settling tank, a pipe connection from the bottom of the settling tank to the settling well said pipe entering the settling well a considerable distance above the bottom thereof, means for maintaining a normal liquid level in said well, a discharge pipe in the settling well the lower end of said pipe being open and arranged near the bottom of the settling well, the upper end of said discharge pipe being carried through the wall of the settling well above the connection between the tank and the wall and below the normal liquid level of said well, heating coils in said tank and in said well, a water jacket surrounding the well below its connection with the settling tank, and means for heating the water in said jacket.

4. An apparatus for separating liquid TNT from liquids of lighter specific gravity, comprising a primary tank, means for accumulating in said tank the liquids to be separated, a settling tank, a connection from the bottom of the primary tank to the settling tank near the bottom of the latter tank, a settling well the bottom of said well being below the bottom of the settling tank, a connection from the bottom of the settling tank to the settling well said connection being a considerable distance above the bottom of said well, an overflow connection from the primary tank to maintain a substantially constant liquid level therein and in the settling tank and well, a discharge pipe in the settling well the lower end of said pipe being open and arranged near the bottom of said well, the upper end of said discharge pipe being carried out of the settling well above the connection with the settling tank and below the normal liquid level, and means for maintaining the liquid at the desired temperature.

5. An apparatus for separating liquid TNT from liquids of lighter specific gravity, comprising a primary tank, means for accumulating in said tank the liquids to be separated, a settling tank, a connection from the bottom of the primary tank to the settling tank near the bottom of the latter tank, a settling well the bottom of said well being below the bottom of the settling tank, a connection from the bottom of the settling tank to the settling well said connection being a

considerable distance above the bottom of said well, an overflow connection from the primary tank to maintain a substantially constant liquid level therein and in the settling tank and well, a discharge pipe in the settling well the lower end of said pipe being open and arranged near the bottom of said well, the upper end of said discharge pipe being carried out of the settling well above the connection with the settling tank and below the normal liquid level, means for maintaining the liquid at the desired temperature, and means for maintaining in the primary tank a constant supply of liquids to be separated.

6. An apparatus for separating liquid TNT from liquids of lighter specific gravity, comprising a primary tank, means for accumulating in said tank the liquids to be separated, a settling tank, a connection from the bottom of the primary tank to the settling tank near the bottom of the latter tank, a settling well the bottom of said well being below the bottom of the settling tank, a connection from the bottom of the settling tank to the settling well said connection being a considerable distance above the bottom of said well, an overflow connection from the primary tank to maintain a substantially constant liquid level therein and in the settling tank and well, a discharge pipe in the settling well the lower end of said pipe being open and arranged near the bottom of said well, the upper end of said discharge pipe being carried out of the settling well above the connection with the settling tank and below the normal liquid level, means for maintaining the liquid at the desired temperature, means for maintaining in the primary tank a constant supply of liquids to be separated, a supplemental settling tank, means connecting said tank to the overflow from the primary tank, a supplemental settling well the bottom of said well being below the bottom of the supplemental settling well said connection being a considerable distance above the bottom of said supplemental well, an overflow connection from the supplemental settling tank to maintain a substantially constant liquid level therein and in the supplemental well, and a discharge pipe in the supplemental settling well the lower end of said pipe being open and arranged near the bottom of said supplemental well, the upper end of said discharge pipe being carried out of the supplemental well above the connection with the supplemental settling tank and below the normal liquid level of said well.

In testimony whereof I hereunto affix my signature.

RICHARD H. BOTS.
